UNITED STATES PATENT OFFICE.

GUSTAV ALBERT ZIMMERMANN, OF REMSCHEID, GERMANY.

SAW.

No. 921,330.

Specification of Letters Patent.

Patented May 11, 1909.

Application filed April 8, 1908. Serial No. 425,949.

To all whom it may concern:

Be it known that I, GUSTAV ALBERT ZIMMERMANN, residing in the city of Remscheid, Rhenish Prussia, Germany, a subject of the 5 Emperor of Germany, have invented a new and useful Improvement in Saws, of which the following is a specification.

My invention has reference to saws and especially to carpenters' and like workmen's 10 saws and it has for its object a new and useful construction of the handle and its combination with the saw blade which allows connecting both parts without riveting or screwing them together.

15 I have shown on the accompanying drawings some modifications of my new saw.

Figure 1 is a side view, Fig. 2 a vertical section of Fig. 1 along line I—I, Fig. 3 is a horizontal section along line II—II of Fig. 1, 20 Figs. 4 and 5 show a modification, and Figs. 6 and 7 are two further modifications of my improved device and Figs. 8 and 9 illustrate horizontal sections of Figs. 6 and 7.

Like letters of reference indicate like parts 25 throughout the drawings.

By *a* is marked the saw blade which at its end is provided with rectangular slots *b*.

c is a back plate having a pressed or 30 stamped out portion in order to form a loop *e* which portion projects through the slot *b* of

the saw blade so that the loop *e* is outside the saw blade and thus enabled to receive a wedge plate *d* which on being forced into said loop *e* Figs. 1-3 causes the blade *a* to be rigidly clamped between the back plate *c* and the wedge *d*. The plate *c* and wedge *d* are 35 connected by headed studs *v* and slots *u* enabling the wedge *d* to be shifted on the plate *c* and inserted into the stamped out

loop *e* or withdrawn therefrom. The plate *c* and wedge *d* are formed to a conical ear or tubular piece *f*, *g* in order to receive the wood handle *s*.

In the modification shown in Figs. 4 and 5 40 the back plate *c* is provided with the tubular portions *h*¹, *h*² having between them a recess into which fits a similar portion *h* projecting

from the wedge *d*. When mounted the portions *h*¹, *h*² form a uniform tube in which is inserted the wood handle *s*.

50

Another variation of my invention is shown in Figs. 6 and 8 in which the plate *c* is provided with a handle tube *k*. This tubular portion is provided with the vertical opposite slots *n* through which the wedge *r* is 55 entered having a head or protuberance *r*¹ which bears against the tube wall as shown and is held in position by means of the handle *s*¹.

As seen from Figs. 7 and 9 the wedge plate 60 *d* may be fitted with a blade spring *p* which bears against the portion or stay *e* filling out the slot *b* and holding thus firmly in position the plate *d* which on its back side has a tongue *c*, both tongue and plate *d* forming 65 part of the tubular portions *h* according to the construction shown in Fig. 1 or Fig. 4. The plate *c*¹ may be provided with a loop *t* for guiding a tongue *c* the protuberance *q* of which limits the movement of the said 70 clamping means by bearing against the said loop *t*. The tongue *c* may be also dispensed with without departing from my invention.

What I claim and desire to be protected by 75 Letters Patent is:

1. In a saw having a handle said handle consisting of a back plate bearing against the saw which is slotted, a loop stamped out of the back plate and engaging the saw slot, a wedge or front plate engaging the loop, said 80 back and front plates forming means to receive the handle as described and set forth.

2. In a saw having a handle, said handle consisting of a back plate bearing against the saw which is slotted, a loop stamped out of 85 the back plate, a wedge or front plate engaging the loop and a spring forming part of the wedge plate and engaging the loop said back and front plates forming means to receive the handle as described and set forth.

GUSTAV ALBERT ZIMMERMANN. [L. S.]
